UNITED STATES PATENT OFFICE

92,792

DESIGN FOR A CASING FOR A UNIPOWER AGITATOR DRIVE

Richard L. Cawood, East Liverpool, Ohio

Application October 13, 1933, Serial No. 49,477

Term of patent 14 years

To all whom it may concern:

Be it known that I, RICHARD L. CAWOOD, a citizen of the United States, residing at East Liverpool, in the county of Columbiana, and State of Ohio, have invented a new, original, and ornamental Design for a Casing for a Unipower Agitator Drive, of which the following is a specification, reference being had to the accompanying drawing, forming part thereof, in which—

Fig. 1 is a perspective view of the article showing my new design, and

Fig. 2 is a top plan view thereof.

I claim:

The ornamental design for a casing for a unipower agitator drive, as shown.

RICHARD L. CAWOOD.
